UNITED STATES PATENT OFFICE.

GEORGE W. BERRY, OF WOLFEBORO, NEW HAMPSHIRE.

EXCELSIOR-CUTTING MACHINE.

1,341,037.

Specification of Letters Patent,

Patented May 25, 1920.

Application filed October 29, 1919. Serial No. 334,188.

To all whom it may concern:

Be it known that I, GEORGE W. BERRY, a citizen of the United States, residing at Wolfeboro, in the county of Carroll and State of New Hampshire, have invented new and useful Improvements in Excelsior-Cutting Machines, of which the following is a specification.

This invention relates chiefly to the means employed in an excelsior cutting machine for guiding the reciprocating face plate which carries the usual scoring and shaving knives.

The invention has for its object to provide face-plate guiding means of simple and durable construction, adapted to compensate for all wear of rubbing parts, to insure movement of the face-plate without loose motion and deviation from a predetermined path, and to permit convenient renewal of worn out parts.

The invention is embodied in the improvements which I will now proceed to describe and claim.

Of the accompanying drawings forming a part of this specification,—

Figure 1 is a front elevation of the machine, the face-plate being lowered.

Fig. 2 is a section on line 2—2 of Fig. 1, omitting the face-plate.

Fig. 3 is a side view of the face-plate.

Fig. 4 is an edge view of the face-plate.

Fig. 5 is a section partly on line 5—5, and partly on line 5^a—5^a of Fig. 2, certain parts shown by Fig. 2 being omitted.

Fig. 6 is a section on line 6—6 of Fig. 1.

Figs. 7 and 8 are side views of the guide-member-carrying bars separated from each other.

Fig. 9 is a section on line 9—9 of Fig. 8.

Fig. 10 is a section on line 10—10 of Fig. 8.

Fig. 11 is a section on line 11—11 of Fig. 7.

Fig. 12 is a section on line 12—12 of Fig. 7.

Fig. 13 is a sectional view of one of the runners.

Fig. 14 is a perspective view of the pitman and face-plate connecting member.

Fig. 15 is a plan view, and

Fig. 16 an end view of the worm on the driving-shaft.

The frame of the machine includes a base

portion 20, and spaced apart uprights 21 55 and 22, these being preferably stout wooden beams.

The reciprocating face-plate 23 (Figs. 3 and 4) which carries the usual scoring or grooving knives 24, and shaving knife 25, of an excelsior cutting machine, is provided at its opposite edges with offset ears 26 to which are rigidly and detachably secured tool steel runners 27 and 27^a, each formed in cross section as shown by Fig. 13. Each 65 runner is longitudinally grooved to receive an edge portion of the face plate, and has oppositely facing inner and outer sides, and an intermediate side at right angles to the inner and outer sides and extending across 70 the edge of the face plate. Said runners slide in vertical guiding structures, which are capable of various adjustments. The guiding structure at the left-hand edge of the face-plate, as viewed in Fig. 1, is here- 75 inafter called the outer guiding structure, for convenience in distinguishing it from the guiding structure at the opposite edge of the face-plate, said outer guiding structure being next described.

To the upright 21 is attached by bolts 28, a fixed elongated outer metal bar, 29, shown in elevation by Fig. 7, and in section by Figs. 11, 12, said bar being provided at intervals with recessed bosses 30, bearing 85 on the upright 21, and receiving the heads of the bolts 28, as best shown by Fig. 5. The fixed bar 29 contacts with the intermediate side of the runner 27, and is provided at one edge with a flange 31, to which is attached 90 an elongated bronze strip or guide member 32, with which the outer side of the runner 27 is in sliding contact, the member 32 being fixed and non-adjustable. To the fixed outer bar 29 is adjustably secured a simi- 95 larly elongated movable or adjustable inner bar 34, shown in elevation by Fig. 8, and in section by Figs. 9 and 10. To one edge of the movable inner bar 34 is fixed an elongated bronze strip or guide member 35, with 100 which the inner side of the runner 27 is in sliding contact. The movable inner bar 34 is provided with transverse slots 36, through which pass headed clamping bolts 37, en- gaged with tapped orifices 38 in the fixed 105 outer bar 29. Said slots and bolts permit the adjustment of the movable bar 34 and its guide member 35 to vary the distance be-

tween the guide members 32 and 35, and compensate for wear of the guide members and of the interposed runner 27.

The outer bar 29 is provided with spaced 5 apart ears 40, tapped to engage set-screws 41 which bear on the inner bar 34, and co-operate with the bolts 37 in securing the bar 34 in any adjusted position.

The inner guiding structure is supported 10 by the upright 22, and includes guiding members 32^a and 35^a, bearing on opposite sides of the runner 27^a and elongated bars 29^a and 34^a supporting said guide members. The bar 29^a contacts with the intermediate 15 side of the runner 27^a. The bars 29^a and 34^a are counterparts, or reversed duplicates of the bars 29 and 34, and are adjustable toward and from the upright 22, to vary the distance between the runners 27 and 27^a, 20 and thus provide additional wear-compensating means.

To this end I make the bolts 28^a in the upright 22 somewhat longer than the corresponding bolts 28, in the upright 21 as 25 shown by Fig. 5, and provide the upright 22 with metal plates 42 (Fig. 6) which are tapped to engage bearing screws 43 extending through the upright 22, and bearing at their inner ends on the bar 29^a. By loosening the nuts on the bolts 28^a, and adjusting the bearing screws 43 inwardly, I am enabled to increase the distance between the upright 22 and the bars 29^a and 34^a.

The described means for guiding the face 35 plate 23 including the inner and outer guiding structures, provide compensation for all wear of rubbing surfaces, and enable the face plate 23 to be kept in a predetermined path of movement without edgewise displacement, such as would cause the paths of 40 the scoring knives 24 during any stroke, to deviate from the paths during a preceding stroke. At each stroke the scoring knives should be in position to deepen the scores 45 or grooves formed in the block at a preceding stroke, so that shavings of uniform width will be detached by the knife 25.

The machine is provided with the usual feed rolls 45 and 46, which respectively engage 50 the lower and upper ends of the wood block 47 to be cut into excelsior, and are intermittently rotated to feed the block toward the face plate 23. The shaft of the lower feed roll 45 is journaled in bearings 48 fixed 55 to the uprights 21 and 22, and the shaft of the upper feed roll 46 is journaled in bearings 49 which are fixed to slides 50 movable vertically on said uprights. Said slides are pulled downward by springs 51 to hold the 60 upper feed roll in engagement with the upper end of the block, and are adapted to be raised to separate said feed roll from the block, by a rock shaft 53 journaled in fixed bearings 54, and provided with pinions 55 meshing with racks 56 fixed to the slides 50,

and with a hand lever 57. The driving shaft 58 is journaled in a bearing 59 on the upright 21, and reciprocates the face plate 23 through a disk 60 having a wrist-pin 61, and a pitman 62 connecting said wrist-pin 70 with a member 63 (Fig. 14), fixed to the lower end of the pitman and jointed to ears 64 (Fig. 5) on the face plate. The member 63 has an ear 63^a bearing on the lower end 75 of the pitman and is provided with holes 64^a for bolts attaching the member to the pitman, the inner side of the member being grooved at 65 to engage one side of the pitman, the latter being of wood. An elongated orifice 66 in the member 63 receives two bearing blocks 67 which are grooved to provide an orifice 68 for the pin which connects the pitman with the face plate. The upper block 67 is held by a wedge-shaped key 68^a driven into a slot 69.

The shaft of the lower feed roll 45 has a worm gear 70, engaging a worm 71, fixed to a vertical shaft section 72. The shaft of the upper feed roll has a worm gear 73 engaging a worm 74, which is adapted to 90 slide on and rotate with the shaft section 72. A clutch 75 connects the shaft section 72 with an upper shaft section 76. A worm gear 77 on the upper shaft section engages a worm of original construction fixed to 95 the driving shaft 58. Said worm includes a helical rib 79 and a sleeve 80 on which said rib is formed. The sleeve is provided with slots 81, extending from its bore nearly to the outer edge of the rib 79, as shown by 10 Fig. 16, the slots rendering the sleeve compressible, so that it may be clamped firmly by screws 82 on the shaft 58, there being no interruption of the continuity of the rib. The form of the rib 79 is such that each 10 complete rotation of the shaft 58 imparts a partial rotation to the shaft sections 76 and 72, and then allows said sections to stop, so that the feed rolls are intermittently rotated to feed the block forward after 11 each cutting movement of the face plate.

I am enabled, by providing the face plate 23 with the tool steel runners 27, detachably secured to the face plate by screws 27^b, to not only renew said runners when they are 11 worn out, but also to make the face plate of a different material, such as aluminum. In practice, I make the entire face plate from a number 12 aluminum mixture, and thereby greatly reduce the weight of the face 12 plate and the power required to reciprocate it, as compared with a face plate made, as heretofore, of iron or steel, the reduction being nearly one hundred per cent.

The bar 29 positively and non-adjustably 13 secured to the upright 21, constitutes a fixed abutment against which the runner 27 is held by the adjustable bar 29^a, so that the face plate is guided in a predetermined path and cannot deviate from said path. 14

Provision is therefore made for preventing any deviation of the cutting knives during their return movement, from the paths in which they move while cutting. This provision insures the formation of shavings of uniform width, and prevents cutting the formation of very narrow or hair-like shavings, which are practically useless.

I claim:

- 10 1. An excelsior cutting machine comprising a pair of spaced apart uprights, a knife-carrying face plate movable in a vertical path between said uprights, and provided at its opposite edges with vertical runners, each presenting parallel outer and inner faces, and an intermediate face at right angles with the outer and inner faces, and a pair of guiding structures including elongated outer bars contacting with the intermediate runner faces, and provided with flanges contacting with the outer runner faces, and elongated inner bars adjustably secured to the outer bars and contacting with the inner runner faces, means positively se-
- 15
- 20

curing the outer bar of one of the guiding structures to one of said uprights, so that said bar is non-adjustable, and means adjustably securing the outer bar of the other guiding structure to the other upright, to permit a wear-compensating variation of the space between the two guiding structures, the said non-adjustable bar constituting a fixed abutment against which one runner of the face plate is held by the corresponding bar of the adjustable guiding structure, whereby deviation of the face plate from a predetermined path is prevented.

2. In an excelsior cutting machine, a knife-carrying face plate having vertical flanges at its edges, and provided with vertical runners, substantially U-shaped in cross section, detachably secured to and covering said flanges.

In testimony whereof I have affixed my signature.

GEORGE W. BERRY.
